FLUID PRESSURE GENERATION

Romeo M. Nardone, East Orange, N. J., assignor
to Eclipse Aviation Corporation, East Orange,
N. J., a corporation of New Jersey

Application June 18, 1937, Serial No. 148,997

3 Claims. (Cl. 123—183)

This invention relates to fluid pressure generation, particularly to the generation of pressure fluid by the ignition of explosive material confined in a suitable container or cartridge, which pressure fluid may, upon generation, be applied to an engine starting mechanism to produce energization thereof.

An object of the invention is to provide a novel arrangement of the elements of an explosive cartridge.

Another object of the invention is to provide novel means for controlling the ignition of the combustible material in an explosive cartridge.

Another object is to provide a novel cartridge housing or breech mechanism including a novel control of the opening, closing and locking of the breech mechanism and a novel interlocking arrangement whereby ignition of the combustible material is rendered impossible in advance of a secured locking of the breech mechanism.

A further object is to provide means for exhausting the chamber of the breech mechanism in advance of the cartridge and for automatically insuring the closing of such an exhaust vent prior to the firing of the cartridge, also for insuring complete evacuation of the chamber in advance of opening the breech mechanism, following the firing of the cartridge; also for regulating rate of delivery of the generated gases to the outlet conduit leading from the breech chamber to the device to be actuated, such as the piston of a servo-motor type of starting mechanism by which initial rotation is imparted to the crankshaft of an internal combustion engine.

These and other objects of the invention will become apparent from inspection of the following specification when read with reference to the accompanying drawings wherein is illustrated the preferred embodiment of the invention. It is to be expressly understood, however, that the drawings are for the purpose of illustration only, and are not designed as a definition of the limits of the invention, reference being had to the appended claims for this purpose.

In the drawings:

Fig. 1 is a longitudinal sectional view of the breech mechanism with the cartridge in position and the igniting mechanism also in operative position;

Fig. 2 is a longitudinal sectional view of that portion of the mechanism shown in Fig. 1 which controls the exhausting of the cartridge chamber, and with the parts shown in the position opposite to that indicated in Fig. 1;

Fig. 3 is a longitudinal sectional view of the

igniting mechanism shown in Fig. 1 but on a larger scale and with the igniting plunger in a position which it occupies whenever the breech is in the unlocked position;

Fig. 4 is a transverse view of certain of the parts as seen along the line 4—4 of Fig. 1; and

Fig. 5 is a transverse view along the line 5—5 of Fig. 1 showing a detail of the locking and exhaust valve operating mechanism.

Fig. 6 is a view in elevation of the structure of Fig. 1, with a showing in longitudinal section of the means for insuring evacuation of the breech chamber in advance of any swinging of the breech cover plate from its closed position;

Fig. 7 is a view, in longitudinal section, of the means for regulating the rate of delivery of the generated gases to the outlet conduit leading from the breech chamber; and

Fig. 8 is a view in perspective of a cartridge constituent.

The cartridge 11 is shown in Fig. 1 as containing a relatively slow burning powder 12 occupying a major portion of the space within the cartridge and separated from a layer 13 of a highly combustible primer charge by an intervening partition 14 of "Cellophane" or equivalent material. As indicated in Fig. 8 this cup-shaped partition 14 not only serves as a dividing wall between the priming charge 13 and the slow burning powder charge 12 but additionally serves as a retainer for particles of fast burning powder of the character constituting the primer charge 13. These particles 15 may be affixed to the Cellophane surface by any suitable means as by first applying a liquid or plastic adhesive such as glue to the Cellophane surface and then depositing the particles 15 upon the surface so treated. If desired both sides of the dividing wall 14 can be treated in this manner but in any event, it is desirable that the side which is adjacent the slow burning powder 12 be so treated, in order to accelerate the process of heat transfer from the priming charge 13 to the slow burning powder 12 and thus insure ignition of the latter. The primer charge 13 is in turn confined in advance of a strip 16 of current conducting metallic material bent into the shape indicated so that one surface lies along the outer metal cap 17 which extends over the end of the cartridge and along its cylindrical side for a certain distance as indicated at 19 where it firmly grips the non-metallic portion of the cartridge casing. The strip of metal is bent to pass through the slotted partition 16a (shown best in Fig. 3) and is again bent so that it will have an

- extending portion 16b in the path of the conical end of a plunger 21 of current conducting material having a head 22 adapted to be urged forward by coiled spring 23, the plunger being slideable within a sleeve 24 of non-conducting material which in turn slides within the boss 26 of the breech cover plate 27, the said cover plate being in two sections, 27 and 28, secured together as indicated at 29.
- 10 The means for normally holding the plunger 21 out of position for transmission of current to the igniting disc 18, and thereby preventing premature ignition—that is, ignition prior to the locking of the breech mechanism—is shown as 15 including an internally threaded sleeve 31 operating upon an externally threaded screw 32 adapted to be threaded axially along guide pins 34 (best shown in Fig. 3) to cause a corresponding axial movement of the non-conducting 20 sleeve 24 and thereby move the head of the plunger 21 from the position indicated in Fig. 1, to the position indicated in Fig. 3 in response to the turning of the sleeve 31 which results whenever the breech handle 41 is moved from the position 25 shown in full lines in Fig. 4 to the position shown in dash lines, such swinging of the handle being effective to turn the threaded sleeve 31 by reason of the inter-engagement of the teeth or splines 46 and 47 of the members 31 and 48 respectively, the latter being the central hub portion of the handle 41. A pin 51 secures said hub 49 of the handle to the stem 52 of the flag or latch 53 which thereby swings with the handle 41 so as to move from a locked to an unlocked 30 position with respect to the dependent leg 61 of the breech casing 62, which leg 61 with the toe 63 constitutes the keeper for the latch or flag 53 and prevents opening of the breech cover prior to the swinging of the handle to the unlocked 35 position, which swinging moves the flag 53 from the full line position indicated in Fig. 5 to the dash line position, and at the same time causes an actuation of the chamber exhausting mechanism now to be described.
- 40 45 The means for automatically exhausting the chamber 71 in advance of the cartridge preferably takes the form of a pair of transverse passages 72 and 73, the latter being vented to the atmosphere and the former serving to connect the chamber 71 with a smaller chamber 74 wherein is located a coiled spring 76 the pressure of which upon a ball type valve 77 is regulable by adjustment of the screw 78. With the flag 53 in the position shown in Fig. 1 and in 45 full lines in Fig. 5 the end 81 of the valve occupying rod 82 sits in the depression 83 in the forward surface of the flag, in which position the rod is sufficiently withdrawn to permit spring 76 to hold valve 77 against the valve seat 85 and 50 therefore prevent communication between the passage 72 and the vent 73. Thus any possibility of escape of the pressure generated by the firing of the cartridge is avoided but after the firing of the cartridge and the swinging of the handle 41 to the breech opening position the corresponding movement of the flag 53 shifts the position of the depression 83 from that indicated at 83a in Fig. 5 to that indicated at 83b in Fig. 5 and thereby creates a cam action which presses 55 the rod 82 forward to the position indicated in Fig. 2, in which position the valve 77 is moved off its seat to allow exhaust of any residual pressure remaining in the chamber 71, the exhaust being in the way of the communicating 60 passages 72, 74 and 73.

After the handle 41 has been moved to the lock releasable position the sectional breech cover 27, 28 may be swung to the breech opening position about the supporting trunnion 94 in which the hinge portion 95 of the breech cover 5 plate is rotatably mounted as indicated at 96. This swinging of the cover plate will operate to eject or at least dislodge the cartridge through the intervening parts 97 and 98, the former being a toe piece on the hinge 95 engageable with 10 the ejector pin 98 in response to the swinging of the cover plate, and the ejector plate 98 being in turn provided with a flange engaging the forward flange on the cartridge to eject the latter.

However, this opening of the cover plate prematurely—that is, in advance of complete evacuation of the chamber 71—is made impossible by the provision of the toe engaging lock 101 shown in Fig. 6. Referring to the said Fig. 6, the lock 101 is shown therein as taking the form of a 20 plunger normally held out of the path of the toe 97 by the action of a compression spring 102 which engages the head or piston portion 103 of the plunger, the said head portion 103 being in turn slideable within the cylindrical housing 25 104 which contains a vent 105 to prevent the building up of a pressure behind the head 103. Abutting the head 103 is a second piston or plunger 107 also slideable in the cylindrical housing 104 and having its face exposed to the pressure of any gases which may remain in the chamber 71 of the bridge mechanism, the said chamber 71 having communication with the smaller chamber 108 into which the piston 107 is movable by the above described spring 102, the path of communication between the two chambers 71 and 108 being indicated at 111. So long as any gases remain unevacuated the pressure set up thereby will urge the piston 107 and hence the locking member 101 into the position indicated at 106, in Fig. 6, in which position the cover plate is held against any opening movement. Meanwhile the evacuation of the gases proceeds by way of the passages 72, 74 and 73, best shown in Fig. 1, till such time as the resulting pressure drop is such as to permit spring 102 to retract the plunger 101 away from interfering relation to the toe 97.

Transmission of electric current to strip 16, (by way of electrical connections, not shown, 50 leading to metal disc 18, spring 23, and plunger 21) creates a temperature rise sufficient for instantaneous ignition of the priming charge 13, and the rapid combustion of the priming charge creates sufficient additional heat to ignite the 55 main charge 12, which thereupon proceeds to burn at a relatively slow rate, to cause a gradual building up of pressure in the chamber 71. As the pressure builds up in chamber 71 the meter valve 121, shown in Fig. 7, moves back 60 within the imposing compression spring 122 mounted in the breech extension 123, to permit a portion of the conduit 124 to become exposed for entry of the gases directly thereto as well as through the restricted openings 25 which function prior to the building up of this predetermined pressure. In this manner the valve serves to regulate the rate of delivery of the generated gases to the part to be moved (not shown) with which the conduit 124 communicates.

This application is a continuation in part of my application No. 107,295 filed October 23, 1936.

What I claim is:

1. A cartridge firing device comprising, in combination, a movable cartridge firing pin, a 75

breech having a cover plate surrounding said firing pin, means for moving said firing pin into position to ignite the powder charge of the cartridge, manually operable means for opening 5 said breech by the withdrawal of the cover plate from closed position, and means responsive to the pressure of the gases resulting from such ignition to prevent operation of said manually operable means until the pressure of said gases 10 has dropped below a fixed, predetermined value.

2. A cartridge firing device comprising, in combination, a movable cartridge firing pin, a breech having a cover plate surrounding said firing pin, means for moving said firing pin into position to ignite the powder charge of the cartridge, means responsive to the pressure of the gases resulting from such ignition to prevent manually opening of the said cover plate so long 15 as any of said gases remain confined within the breech chamber, means distinct from said cover 20

plate for venting said breech chamber of all said gases, and means for automatically closing said vent in response to locking of the cover plate in the closed position.

3. A cartridge firing device comprising, in 5 combination, a movable cartridge firing pin, a breech having a cover plate surrounding said firing pin, means for moving said firing pin into position to ignite the powder charge of the cartridge, means responsive to the pressure of the 10 gases resulting from such ignition to hold said cover plate in the closed position so long as any of said gases remain confined within the breech chamber, a conduit leading from said breech chamber to the point of utilization of the generated gases, and means shiftable by pressure variations to regulate the rate of delivery of the 15 gases to said conduit.
